CLAIM

The ornamental design for a three-wheeled electric vehicle, as shown and described.

DESCRIPTION

The patent or application file contains at least one drawing executed in color. Copies of this patent or patent application publication with color drawing(s) will be provided by the Office upon request and payment of the necessary fee.

1.1 is a top, right-side perspective view of a three-wheeled electric vehicle embodying our new design;

1.2 is a top, left-side perspective view thereof;

1.3 is a front elevation view thereof;

1.4 is a back elevation view thereof;

1.5 is a left-side elevation view thereof;

1.6 is a right-side elevation view thereof;

1.7 is a top plan view thereof; and

1.8 is a bottom plan view thereof.

The dot-dash broken lines represent boundaries of the three-wheeled electric vehicle that form no part of the claimed design.
